US00D914057S

(12) **United States Design Patent** (10) **Patent No.:** **US D914,057 S**
Clymer et al. (45) **Date of Patent:** **** Mar. 23, 2021**

(54) **DISPLAY SCREEN OR PORTION THEREOF WITH GRAPHICAL USER INTERFACE**

(71) Applicant: **Lutron Technology Company LLC**,
Coopersburg, PA (US)

(72) Inventors: **Erica L. Clymer**, Northampton, PA (US); **Brian Michael Courtney**, Bethlehem, PA (US); **Sanjeev Kumar**, Harleysville, PA (US); **Sandeep Mudabail Raghuram**, Emmaus, PA (US); **Richard M. Walsh, III**, Bethlehem, PA (US); **Jennifer Wong**, Breinigsville, PA (US)

(73) Assignee: **Lutron Technology Company LLC**,
Coopersburg, PA (US)

(**) Term: **15 Years**

(21) Appl. No.: **29/649,798**

(22) Filed: **Jun. 1, 2018**

Related U.S. Application Data

(63) Continuation of application No. 29/562,240, filed on Apr. 24, 2016, now Pat. No. Des. 822,034.

(57) **CLAIM**

The ornamental design for a display screen or portion thereof with graphical user interface, as shown and described.

DESCRIPTION

The sole FIGURE shows a display screen or portion thereof with graphical user interface showing our new design. The dashed broken lines represent a display screen or portion thereof and form no part of the claimed design. Shading represents contrast.
